DISPLAY DEVICE

Samuel I. Burd and Martin M. Burd,
Mellrose Park, Pa.

Application March 7, 1944, Serial No. 525,456

2 Claims. (Cl. 35—56)

Our invention relates to a display device and more particularly to a device adapted for the display of stockings. One object of our invention is to produce an improved display device of the character set forth.

A further object of our invention is to produce a display device which, in addition to displaying a full length ladies' hose, also intermittently stretches a given part of the hose, such, for example, as the toe, in order to demonstrate the elasticity, the durability, and the quality of the fabric.

A further object of our invention is to produce a display device of the character set forth which is inexpensive to manufacture and sell and which can be easily mounted in the limited space available in a display window, with the operating part of the mechanism concealed so that the display may present a neat and attractive appearance.

These and other objects are effected by our invention as will be apparent from the following description and claims taken in connection with the accompanying drawing, forming a part of this invention, in which:

Fig. 1 is a diagrammatic view in side elevation, illustrating the display device embodying our invention shown applied to the stretching of the toe of a ladies' stocking;

Fig. 2 is a section, on an enlarged scale, along lines II—II of Fig. 1, showing the display device in its collapsed or non-stretching position;

Fig. 3 is a view similar to Fig. 2, showing the display device in its expanded or stretching position;

Fig. 4 is a section, on an enlarged scale, on line IV—IV of Fig. 1; and

Fig. 5 is a section, on an enlarged scale, on line V—V of Fig. 1.

Referring to Fig. 1, 10 designates a form simulating the foot, leg and the lower portion of the thigh of a feminine leg. Ladies' hose 12 is drawn over and draped upon the form 10 so as to simulate a demonstration by a living model. The form 10 may be made of any desired material such as cardboard, or if it is desired to transmit light therethrough, it may be made from some translucent material which will enhance the appearance of the stocking. Alternatively, the form 10 may be made of material which will provide adequate background for the sheer fabric of the stocking. The form 10 is suitably secured to a display board 14, which is shown broken away in Fig. 1, but the size, contour and decoration of which form no part of the present invention. The purpose of the board 14 is to support the

display device and to conceal from view any part of the mechanism which might otherwise mar the appearance. The form 10 may be suitably secured to the board 14 either permanently or in a detachable manner, as by wing nuts or the like. 5 16. A flexible shaft 18 extends through the form 10 and through an opening in the board 14, so as to be actuated by a motor 20 suitably supported behind the board 14 so as to be concealed from view. The exact construction of the shaft 18 is not shown, for the reason that any approved design available on the market may be employed. The shaft 18 conforms to the bend in the knee of the stocking and also to the bend 10 along the ankle and instep of the stocking, and the lower end thereof is supported in a suitable bearing 22 carried by a spider 24 which, in turn, is suitably carried by or secured to the lower portion of the form 10 at a point immediately in 15 advance of the toe portion 36 of the stocking. The shaft 18 carries a cam 26 which is adapted to coact with cam surfaces 28 formed in the juxtaposed ends of two members 30 and 32. The members 30 and 32, when in abutment along 20 their inner edges, constitute a form for the toe portion 36 of the stocking. The members 30 and 32 are urged towards each other by a pair of torsion springs 34 and are adapted to be spread apart by the cam 26.

30 In Figs. 2, 4 and 5, the cam 26 is shown in its ineffective position with the members 30 and 32 drawn into close abutment by the springs 34. In this position, the toe of the stocking is not stretched. When the motor 20 is turned on so 35 as to revolve the shaft 18 at the desired R. P. M., the cam 26 will rotate with the shaft 18 and every time the cam 26 assumes the position shown in Fig. 3, the members 30 and 32 are spaced apart and the stocking toe 36 is stretched. It will be 40 noted that the leg form 10 stops at a point at, or slightly past, the middle of the instep so as to leave the toe portion of the foot unsupported, except by the members 30 and 32, whereby, when the members 30 and 32 are separated by the cam 45 26, the stretched fabric will be more clearly visible and would make better contrast with the portions of the stocking which are supported by the continuous surface of the form. This greatly enhances the value of the display device since it 50 emphasizes the quality of the knitting and the capacity of the fabric to withstand stretching.

Also, since the form is bent to represent the position of the knee in a natural sitting posture, the fabric of the stocking is somewhat stretched 55 at the knee, thus also contrasting with the un-

stretched portions covering the leg from above and below the knee.

While we have shown the mechanism applied for stretching the toe portion of the stocking, it is obvious that the members 30 and 32 and cam 26 can be caused to act along the heel, ankle, calf or any portion of the stocking, or a plurality of members 30, 32 and cams 26 can be mounted on the shaft 18 simultaneously to stretch two or more portions of the stocking.

What we claim is:

1. A ladies' stocking display device comprising a vertically-disposed board, a form simulating the leg of a person in sitting position carried by one side of said board and adapted to have a stocking drawn thereover, said form including vertically-disposed calf, knee, and ankle portions, and substantially horizontally-disposed foot and lower thigh portions, the foot portion of said form terminating in advance of the toe portion of the stocking, whereby the toe portion of said stocking is unsupported by said form, a motor carried by the opposite side of said board, a flexible shaft

5 operatively connected to said motor and projecting through said board, said shaft extending through and being bent to conform to the shape of said form, a bearing carried by the foot portion of said form for supporting the free end of said shaft, a pair of juxtaposed separable members adapted to support the toe portion of the stocking, a cam rotatable by said shaft and disposed between said members, a spring normally biased said members against the opposite sides of said cam, said members and said cam being so constructed and arranged that, in one position of said cam, said members and said cam fill, but do not expand, the toe of said stocking, and in 15 another position of said cam, said members are separated so as to expand said toe portion.

2. The structure recited in claim 1 in which the central portions of the contiguous sides of said members are provided with cam faces co-acting with said cam.
